UNITED STATES PATENT OFFICE.

JAMES C. REAMER AND MICHAEL POSEDEL, OF SEATTLE, WASHINGTON.

DESIGN FOR A CHILD'S COMBINATION NURSERY AND HIGH CHAIR.

50,587.

Specification for Design.

Patented Apr. 10, 1917.

Application filed June 19, 1916. Serial No. 104,624. Term of patent 7 years.

To all whom it may concern:

Be it known that we, JAMES C. REAMER and MICHAEL POSEDEL, citizens of the United States, residing at Seattle, in the county of King and State of Washington, have invented a new, original, and ornamental Design for a Child's Combination Nursery and High Chair, of which the following is a specification, reference being had to the accompanying drawing, forming a part thereof.

The figure of the drawing is a perspective view of our new design for a child's nursery chair.

We claim:

The design for a child's combination nursery and high chair substantially as shown.

Signed at Everett, in the county of Snohomish, and State of Washington, this thirteenth day of June, 1916.

JAMES C. REAMER.
MICHAEL POSEDEL.
